UNITED STATES PATENT OFFICE.

JAMES W. SLOAN, OF TULSA, OKLAHOMA.

BLANK AND METHOD FOR MANUFACTURE OF BAILER-BOTTOMS.

1,339,722.

Specification of Letters Patent. Patented May 11, 1920.

Application filed September 20, 1917. Serial No. 192,349.

To all whom it may concern:

Be it known that I, JAMES W. SLOAN, a citizen of the United States, and a resident of the city of Tulsa, in the county of Tulsa, 5 and State of Oklahoma, have invented certain new and useful Improvements in Blanks and Methods for Manufacture of Bailer-Bottoms; and I do hereby declare that the following is a full, clear, and exact 10 description of the same, reference being had to the accompanying drawings, and to the numerals of reference marked thereon, which form a part of this specification.

Bailer bottoms as heretofore constructed 15 have usually been forged, which operation is quite expensive, making the bottoms too costly. It is an object of this invention to provide a method of making bailer bottoms by first forming a blank in the form of an 20 integral casting which is then machined down to the proper proportion, after which the valve member or plunger is cut from its seat member, thereby providing a bailer bottom which is inexpensive in construction 25 and which is quickly made.

It is further an object of this invention to provide a reinforced plunger or valve member which when cut from its seat is retained in place and can never be lost from 30 the rest of the bottom and to so construct the same that it automatically opens and closes and is limited in its opening by the construction thereof.

The invention (in a preferred form) is 35 illustrated in the drawings and hereinafter more fully described.

On the drawings:

Figure 1 is a fragmentary sectional view 40 of a vertical bore or shaft in which a bailing machine embodying my invention has been inserted.

Fig. 2 is a similar view showing the bailing mechanism fully lowered and valve opened with the column of liquid to be 45 bailed above the bailer bottom.

Fig. 3 is a similar view illustrating a tong attached to the valve member for the purpose of elevating the entire mechanism out of the bore should the ordinary bail 50 attached to the tube be broken.

Fig. 4 is a view illustrating the bailer bottom as it is cast.

Fig. 5 is a view showing the same after it has been machined down and the plunger 55 cut from the cylinder or rest of the bottom member.

Fig. 6 is an enlarged fragmentary detail of the lower end of the pipe showing the bailer bottom attached thereto and the plunger slightly elevated.

Fig. 7 is a transverse section taken through the plunger and bailer bottom.

As shown on the drawings:

1, indicates the earth material, 2, indicates the bore therein, 3, indicates any suitable 65 form of hoist mechanism and 4, the hoist cable. Inserted in the bore 2, is the bailing machine, which comprises a tube 5, of any suitable construction having secured thereon a bail 6, to which is secured one end of the 70 cable 4.

The bailer bottom is made in an integral casting after which it is machined down to the proper dimensions and the plunger member is then cut from the bottom. Said 75 device comprises, as shown in Figs. 4, 5 and 6, a bailer bottom or cylindrical member 7, machined down to provide an annular rib 8, on which the tube 5 rests and which limits the telescoping of the bottom into the tube. 80 The bottom 7, is rigidly secured to the lower end of the tube by means of rivets 9, or other suitable means. After the parts are machined down to the proper size the plunger member is cut from the bottom 7, forming 85 a complementary valve seat 10. Said plunger comprises a central conically shaped valve member 11, having an upwardly directed stem 12, integral therewith which is provided with a plurality of grooves, teeth 90 or other suitable means by means of which the same can be readily grasped by a tong 17, or combination socket.

Integrally connected with the under side 95 of the valve closure 11, is a shank or stem 12^a, which as shown is provided at its lower end with a head 16, having shoulders 13, adapted to engage under the bailer bottom to limit the unseating of the valve or plunger. Also integral with said valve 11, and 100 with the shank 12^a, are ribs 14, and the lower end of the closure is provided with an aperture 15, by means of which a tube or other suitable means may be attached when desired.

105 The operation is as follows:

The valve member 11 as a whole is made of a single casting as shown in Fig. 4, after which the same is machined down to the proper proportion providing the rib 8, for 110 the purpose hereinbefore specified. After the parts are machined down to the proper

size the stem 12, is grooved or scored as shown and the valve closure 11, is cut from the bottom member 7, which provides a complementary valve and valve seat, as shown. 5 The bottom 7, is inserted in the tube and the rib 8, limits the movement thereof and the two are riveted together. The device is inserted into the bore as shown in Fig. 1, 2 or 3 in a well known manner by the use of 10 any suitable hoisting mechanism and by its own weight and gravity drops to the bottom of the bore. When the pressure of the column of water as shown in Fig. 2 becomes sufficiently great, the valve member 11, is 15 elevated from its seat, permitting the water to flow into the tube through the open valve until the tube drops to its lowest limit of movement, as shown in Fig. 2. In this position the opening of the valve member is limited by means of the head 16, on the lower end of the plunger, the bottom resting on the shoulders 13. As the bailer is elevated from the bore to clear the water or other material therefrom the valve automatically 20 seats by the pressure of the water and by its own gravity, thereby trapping the water within the tube permitting the same to be elevated with the tube out of the bore and to be dumped therefrom. If it is desired to 25 leave a supply of water in the bore to facilitate the boring operation, or if it is desired to lower water into the bore a suitable device may be attached to the plunger for this purpose by means of the aperture 15. This 30 may also be accomplished by lowering the tube 5, filled with water, into the bore and then inserting the tongs 17 and removing the tube by the engagement of the tongs with the stem 12. 35 By referring to Fig. 3, it will be noted, that should the bailer or other parts of the tube mechanism become broken the same may be elevated from the bore by means of suitable tongs 17, which are dropped into 40

the tube and grapple the stem 12, engaging 45 the teeth thereon and by means of which the mechanism as a whole may be removed from the bore.

From the construction disclosed, it will be noted that the device is very cheap to construct and is made from an integral casting and that it is not necessary to use any complicated or expensive machine in the making of the same. 50

Many details of construction may be varied and numerous changes may be made without departing from the principles of this invention and I therefore do not desire to limit the application for patent otherwise than necessitated by the prior art. 55 60

I claim as my invention:

1. A blank for constructing a device of the class described comprising a cylindrical shell closed at one end, a boss projecting centrally from the outer face of said end 65 and a stem projecting centrally from the inner face of said end narrow at the base and broadening toward its end.

2. A blank for constructing a device of the class described comprising a circular 70 member, a boss projecting centrally from one face of said member and a stem projecting centrally from the opposite face of said member narrow at the base and broadening toward its end. 75

3. A method for constructing a bailer bottom comprising casting a blank and then cutting the blank into two portions one forming the valve member and the other the valve seat. 80

In testimony whereof I have hereunto subscribed my name in the presence of two subscribing witnesses.

JAMES W. SLOAN.
